GARMENT BAGGER

Robert E. Williams, The Dalles, Oreg.

Application May 23, 1939, Serial No. 275,325

1 Claim. (Cl. 226—18)

This invention relates to clothes baggers and the primary object of the invention is to provide a device for placing bags over garments in cleaning establishments and stores, for protecting them from dust, dirt and so forth.

In the use of my new and improved clothes bagger the operation of placing a bag over clothes becomes a simple matter, therefore the use of transparent bags for covering clothes in stores where they are merchandised will become a general practice, due to the ease of removing the bag and bagging the garments.

A still further object of my invention is to provide a clothes bagger mechanism that is easy to install to the ceiling of a room and that gives ample clearance underneath and free movement within the room.

A still further object of my invention is to permit the free use of the operator's hands while bagging the clothes.

These and other incidental objects will be apparent in the drawing and specification.

Referring to the drawing:

Figure 1 is a side view of my new and improved clothes bagger, having a clothes bag clipped thereto.

Figure 2 is a side view of Figure 1 wherein the clothes bag is in raised position ready to be brought down over the garment.

Figure 3 is a fragmentary side section view of my new and improved clothes bagger.

Figure 4 is a detail front view of the pulley system.

Figure 5 is a sectional view of Figure 4, looking in the direction indicated.

Figure 6 is a plan view of Figure 4.

In the drawing:

My new and improved clothes bagger consists of a tubular main body member 1, secured to the ceiling 2 by suitable fastening means 3, which may be secured to the ceiling by screws or bolts. A special fitting or coupling 4 is provided for joining the lower tube 5 with the upper tube 6. The reason for providing a coupling 4 is to provide a standard length mechanism or tube 5 for encasing the working parts of the bagging machine. This construction provides for a standard clearance from the bottom portion or hook 7 above the floor line, due to the fact that the tube 6 can be made of such a length as to provide for the proper clearance. This is one of the important details of my new and improved clothes bagger.

The fitting or coupling 4 is slotted at 8 and has a pulley 9 mounted thereon to shaft 10. A cord 11 is trained about the pulley 9 and down

through the tube 5 and under the pulley 12, which is journaled to the shaft 13 secured to the upper portion of the weight 14 at 15. The cord 11 is then brought up the tube and looped over the pin 16 secured within the fitting or coupling 4. The end 17 of the cord could be directly connected to the upper end of the weight 14, but the assembly shown multiplies the travel of clip 18, thereby keeping the overall length of the tube 5 to a minimum. There are a number of clips 18 secured to the cord 11 and are provided to accommodate different lengths of bags as indicated by numeral 19.

In the operation of my new and improved clothes bagger, the end 11A of the cord 11 is grasped by the operator and pulled downward, the clip 18 is clipped to the upper portion of the bag and the end or hook 7 is trained into the hole 20 of the bag. On the releasing of the end 11A of the cord 11 the bag will be raised by the weight 14 to the position shown in Figure 2, and held in this position while the operator arranges the clothes upon the hook 7, the lower end 21 of the bag 19 is then grasped and pulled down over the garments, the clips 18 releasing the same as this operation is performed. This completes a cycle of operation of my clothes bagger. It will be noted that there are no special tubes that are slotted to accomplish the operation of my bagger and that it is simple of construction, making it practical from a production standpoint.

I do not wish to be limited to the particular mechanism employed, as other forms of construction may be used, still coming within the scope of the claim to follow.

What I claim is:

A clothes bagger, including a hollow standard, comprising an upper section and a lower section, means at the bottom of the lower section to support a garment, a coupling uniting the sections formed with a slot, a roller in the coupling, a pin in the coupling, a cord connected at one end to the pin and extended over the roller and through the slot to the exterior of the coupling, a weight movable in the standard and supported on the cord intermediate the pin and roller, and a clothes supporting hook at the lower end of the standard, a clip on the cord to attach a bag, the upper section of the standard providing merely a support from an overhead fixture and being replaceable by sections of different lengths to dispose the lower end of the standard at a proper height from the floor without disturbing the relation or arrangement of any of the operating parts.

ROBERT E. WILLIAMS.
